UNITED STATES PATENT OFFICE.

JOHN DESMOND, OF WILMETTE, ILLINOIS, ASSIGNOR, BY MESNE ASSIGNMENTS, TO
TAYLOR MANUFACTURING COMPANY, A CORPORATION OF ILLINOIS.

PNEUMATIC STARTER FOR INTERNAL-COMBUSTION ENGINES.

1,186,974.

Specification of Letters Patent. Patented June 13, 1916.

Application filed June 15, 1914. Serial No. 845,194.

To all whom it may concern:

Be it known that I, JOHN DESMOND, a citizen of the United States, residing at Wilmette, in the county of Cook and State 5 of Illinois, have invented certain new and useful Improvements in Pneumatic Starters for Internal-Combustion Engines, of which the following is a specification.

My invention relates to pneumatic starters for internal combustion engines and has especial reference to devices of this character as applied to propelling engines of automobiles.

The starting, air motor exemplified herein, is of the same general type as that disclosed in my copending application filed November 11th, 1912 and bearing Serial No. 730,581.

Some of the objects of my present invention are to generally improve the structure of air, starting motors, and means of their application to engines to be started and to improve means for controlling the air under pressure, which is necessary for their 25 operation.

Other and further objects of my invention will become readily apparent, to persons skilled in the art, from a consideration of the following description when taken in 30 conjunction with the drawings, wherein—

Figure 1 shows my engine starter as it appears when applied to an automobile of the Ford type. Fig. 2 is a section, taken on line 2—2 of Fig. 1. Fig. 3 is a transverse section, taken on line 3—3 of Fig. 7. Fig. 4 is a transverse section taken on line 4—4 of Fig. 3, looking in the direction of the arrows and showing the end of the piston. Fig. 5 is a similar section taken on line 5—5 of Fig. 3, looking in the direction of the arrows. Fig. 6 is a detail of a portion of the two part plug that is adapted to fit within the bore of the piston for holding the flexible piston rod in connection therewith. Fig. 45 7 is a section taken on line 7—7 of Fig. 3, looking in the direction of the arrows. Fig. 8 is a transverse, broken away detail taken on line 8—8 of Fig. 7. Fig. 9 is a vertical, axial section of the controlling valve, for 50 controlling the air admitted to the pneumatic motor, which valve forms subject matter of a copending application filed contemporaneously herewith. Fig. 10 is a trans-

verse section of the same taken on line 10—10 of Fig. 9. Figs. 11 shows a steering 55 post of an automobile and the spark controlling lever and means associated therewith to lock the valve and prevent its use when the spark controlling lever is in a predetermined position. Fig. 12 is a transverse section taken on line 12—12 of Fig. 11. Fig. 13 is a section taken on line 13—13 of Fig. 12.

In all the views the same reference characters are employed to indicate similar parts.

In the use of my apparatus a single impulse of air is applied to a piston, that is adapted to be freely reciprocated within the cylinder, and which is connected by a flexible connection to the periphery of a wheel 70 that may be temporarily connected in driving relation with the shaft of the engine to be started. The single impulse of air, or the single cycle of operation of the piston, will serve to rotate the engine shaft sufficiently to cause the engine to become self propelling. After the piston has moved to the full extent of its power stroke, or a sufficient portion thereof, it will be automatically returned to its initial position by 80 means of a spring, intended for the purpose, after the engine has become disassociated from the starting motor.

15 is a cylinder of my pneumatic motor, such as a seamless brass tube, provided with 85 a cap 16 at its free end, in which is a perforation 17. The other end of the cylinder is connected to a head 18 which is preferably a part of the casing 19. A piston, generally indicated by 20, consists of an inner sleeve 21 and an outer sleeve 22, between which is contained a leather packing cup 23. The piston sleeve 21 is provided with a radial flange 24, slightly smaller in diameter than the interior bore of the cylinder 15, for support of the rear surface of the packing cup. The sleeve 22 is provided with a similar flange 25 which affords a guide for the front end of the piston, within the cylinder. The bore of the sleeve 21 is tapered to contain a two part tapered plug 26—26'. This plug snugly fits the taper in the sleeve 21 and contains therebetween a flexible piston rod or ribbon 27. The semi-circular plugs are held together as by a dowel pin 28 105 which passes through a perforation made in

the flexible piston rod, or connection 27. A further means to prevent the piston rod from slipping between the surfaces of the plug 26—26' is the fact that it is bent upon itself to provide an enlargement, as at 29.

The head 18 is provided with an interiorly extending flange 30, upon which rests a stuffing box 31, for containing packing 31' for the flexible piston rod 27. A disk 32 overlies the flange 33 of the stuffing box and is secured to the inwardly extending flange 30, as by screws 34. The disk is provided with an elongated slot 35 through which the piston rod 27 will freely pass. A fitting 36 is adapted to screw into the head 18 and is the means of connecting the air induction pipe 37 to the cylinder. The inner sleeve 21 of the piston, rests against the disk 32, when the former is in its retracted position, and I therefore provide holes or notches 38 in this portion of the piston so that air coming through the pipe 37 may pass under the piston for application to all of its parts. The annular casing 19 is provided with laterally projecting hollow bosses 39 and 40 affording bearings for the shaft 41. The shaft 41 has secured to it a ratchet wheel 42. A bushing, or sleeve 43, surrounds the shaft 41 and extends from the ratchet wheel 42 to the removable side plate 44 of the casing 19. The wheel 45 surrounds the bushing, and is provided with a projecting hub 46. On one side it contains a recess 47 in which the ratchet wheel 42 and pawl 48 are inclosed, the pawl being connectible with the ratchet wheel, to rotate the same. The pawl 48 is pivoted, as at 49, to the radial web 50 of the wheel 45. The pawl is resiliently held in its depressed or engaging position with the ratchet wheel 42, when released, by means of the resilient spring 51, which is secured to the rim of the casing 19. A lug 52 secured to the plate 44 is provided with an angular surface 53 which confronts a similarly tapered rear surface 54, of the pawl 48, so that when this rear surface of the pawl is held against the lug, as when the wheel 45 is held in retracted position, the front end of the pawl will thereby be lifted from contact with the teeth of the ratchet wheel, as clearly shown in Fig. 8.

On the other side of the web 50 of the wheel 45 is an annular recess 55, in which is contained a spiral flat ribbon spring 56. The inner end of this spring is connected to the hub 46 and the sleeve 53 by means of a pin 57, the outer end being connected to the side wall 44 of the casing 19, as by a pin 58. The flexible piston rod 27 is secured to the rim 45' of the wheel, by screws, as at 59. The retracting spring 56 is of sufficient strength to yieldingly hold the wheel 45 in its retracted position, forcing the rear annular surface of the pawl 48 in contact

with the angular surface 53 of the stationary lug 52, thereby tilting the front end of the pawl clear of the ratchet wheel 42 so that the shaft 41 and the ratchet wheel 42 may be rotated, in clockwise direction, viewing Fig. 8, without the teeth of the ratchet wheel making contact with the pawl. As soon as tension is applied to the piston 20, of the cylinder 15, which causes it to move out toward the free end, on its power stroke, the piston rod 27, will rotate the wheel 45 and thereupon the spring 51 will depress the front end of the pawl 48, the rear end having been relieved from the effect of the lug 52, and the pawl will then engage the ratchet teeth of the ratchet wheel 42 to rotate the engine shaft 41.

An attaching clip 60, for securing the casing 19 in proper axial relation with the motor shaft 41, of the automobile engine, and especially when the device is applied to a Ford automobile, as shown in Fig. 1, consists of a piece of sheet metal bent substantially at right angles, a part 61 being substantially the same configuration as the lower portion of the casing 19 and secured thereto as by screws 62, has laterally extending ears 63 and 64, the horizontal portions of such projections or ears being perforated for reception of one bolt member of each of the yokes 65 and 66 that are employed to surround the vehicle spring 67 and hold it in proper position with reference to the supporting cross sill 68 of the automobile. In the particular exemplification the shaft 41 is a substantial extension of the engine shaft 70, it having a squared end 41^a that enters a squared orifice in the sleeve 71, the latter being secured to the shaft 70, by means of a pin 72, and which sleeve carries a sprocket wheel 73. Overlying the sleeve 71 is a belt pulley 74 secured thereto, as by a screw 75. The outer end of the shaft 41 is also squared, as at 41^b, so that the engine may be started by the ordinary starting crank when the cap 76 is unscrewed and removed from the screw threaded hub 39, without interference by the pneumatic starter.

A controlling valve 80, for admitting air from any suitable source of air supply through the pipe 81, to the pipe 37, and from thence into the pneumatic motor, is provided with a laterally and upwardly extending arm 82, and a foot lever 83, hinged as at 84. The lever is held normally in elevated position by means of a spring 85. The valve structure 80 contains three valves, all of which are operated by movement of the lever 83. The lower end of the valve casing is closed by the screw cap 86, in which is secured the air supply pipe 81. The valve 87, normally closes a port 88, an open helical spring 89, serving to accomplish this purpose when the valve is not restrained. Another valve 90, normally closes the port

91, and is held in closed position, when not restrained, by means of a spring 92, that normally rests upon the upper surface of the valve 87. These two valves provide a double seal between the inlet pipe 81 and the outlet pipe 37, when they are closed. A hollow sleeve 93 provided with a central bore 94 terminating in a valve seat 95 at one end and provided with transverse bores 96—96 10 at the other end, is freely slideable in the bore 97. When the sleeve 93 is in the position shown in Fig. 9, the pneumatic motor is vented to the outside atmosphere by the air entering the chamber 99 and passing 15 out through the transverse bores 96 and the axial bore 94, and through grooves 100 made in the side surface of the valve plug 101. The plug 101 carries a valve 102 on its lower end adapted to neatly fit the 20 valve seat 95 carried by the sleeve 93. The plug 101 is provided with an enlarged head 104 against which the spring 85 bears, and with which the lever 83 makes contact when it is depressed.

25 When it is desired to start the pneumatic motor the foot lever 83 is depressed until the valve 102 closes the vent port 95, in the sleeve 93, thereby closing the motor vent. A further depression of the lever 83 will cause 30 the opening of the valve 90, because the sleeve 93 is connected thereto, as by means of a connection 93' which may be a separate or integral part of either the sleeve or the valve 90. Thereupon the valve 87 will be 35 opened by the stem 90', of the valve 90 engaging the upper surface of the valve 87. Air will now pass from the source of air supply to the pipe 81, and through the valve into the pipe 27 and from thence into the 40 cylinder 15 between the head 18 and the piston 20, causing the piston to move slidably rearwardly of the cylinder toward the free end thereof, carrying the flexible piston rod 27 with it and rotating the wheel 45. 45 The piston rod 27 makes one complete turn around the wheel 45, and the wheel will be rotated one complete revolution by the time the piston 20 reaches the full limit of its power stroke, within the cylinder 15. As 50 soon as the wheel 45 begins to move, the pawl 48 will no longer be influenced by the angular surface of the projecting lug 52, and the spring 51 will depress the front end of the pawl into engagement with the teeth of the ratchet wheel 42, thereby beginning to rotate the shaft 41 of the engine immediately upon the movement of the piston 27. When the engine becomes self propelling and the cylinder is exhausted of air the spring 56 55 will return the wheel 45 back to its normal position until the pawl 40 again rests upon the projection 52, as clearly shown in Fig. 8, thereby lifting the pawl from contact with the ratchet wheel and preventing any noise that might otherwise ensue by the ro-

tating ratchet wheel engaging the pawl. Any back firing of the engine will cause the wheel 45 to be returned to its normal position and the removal of the pawl from the ratchet teeth by lifting its engaging end so 70 that there will be no danger of injuring the pawl or the teeth upon the ratchet wheel from such an occurrence.

After the engine has become self propelling, foot pressure is removed from the lever 75 83 when the valve 87 will first be closed. Then the valve 90, which is preferably a soft valve and thereby insures a more complete closure between the inlet and outlet pipes of the valve, will be closed, after which the 80 further extended upward movement of the lever 83 will open the vent valve 102 and cause the air that has heretofore been contained within the cylinder 15 to escape 85 through the pipe 37 and through the chamber 99, the transverse bores 96, and the axial bore 94, of the sleeve 93, and from thence through the grooves 100—100 of the plug 101, to the outside atmosphere, thereby permitting the spring 56 to return the piston 20 90 to the normal position shown in Fig. 3.

In order that the lever 83 may not be depressed until the spark has been properly retarded, by the usual means, to prevent back firing, I provide a bolt for locking the lever 83 in its elevated position, which means is controlled by operation of the spark lever. The spark lever 105, carried on the steering post 106, is secured to a substantially vertical shaft 108, which when rotated will control the spark mechanism through an arm 109 and the usual rod 110. Projecting from the same shaft 108, is another arm 111 which is connected by a rod 112 to a bell crank 113, pivoted as at 114. This bell crank reciprocates a bolt 115 which finds bearings in brackets 116—116. Projecting downwardly from the foot lever 83, is a lug 117. When the shaft 108 is rotated, by the spark lever 105 to advance the spark, the apparatus is 100 positioned as shown in full lines, in Fig. 12, the bolt 115 being shoved forward into the path of the lug 117, on the foot lever 83, so that when the spark is advanced the foot lever 83 can not be depressed for the purpose 105 of operating the starting mechanism owing to the position of the bolt 115. Now when the spark is retarded, which is the proper condition when the engine is to be started, the apparatus in Fig. 12 will assume the 110 positions shown in dotted lines, whereupon the bolt 115 will be withdrawn from the path of the lug 117, so that the foot lever may now be depressed to admit air into the 115 starting motor.

120 While I have herein shown and described a single embodiment of my invention, it is for the purpose of description only, and not with any intention of limiting the claims 125 to the single exemplification disclosed.

Having described my invention, what I claim is:

1. A pneumatic engine starter comprising a circular casing; a wheel within the casing; a shaft upon which the wheel is adapted to be freely rotated; a cylinder connected tangentially to the casing; a piston in the cylinder; a flexible connector connecting said piston to the wheel to rotate the latter; means to rotate the wheel in opposite direction to return the piston; means to connect the wheel and shaft to rotate the latter, operable by initial movement of the wheel, and a pipe, to admit air under pressure in the cylinder behind the piston.
2. In a pneumatic engine starter, the combination of a rotor casing, a hollow head projecting therefrom, a tangentially disposed cylinder connected with and supported by said head, a piston within the cylinder, a rotor, a connection responsive to rotor movement between the engine and rotor, and a connection between the rotor and piston.
3. In a pneumatic engine starter, the combination of a rotor casing, a hollow head projecting therefrom, a tangentially disposed cylinder connected with and supported by said head, a piston within the cylinder, a rotor, a connection operable in response to rotor movement between the engine and rotor, and a flexible connector, one end portion

of which is wound upon the rotor, the other end being connected to the piston.

4. In a pneumatic engine starter, the combination of a rotor casing, a head projecting therefrom and formed integral therewith, a tangentially disposed cylinder connected with said head, a piston within the cylinder, a rotor, a connection operable in response to rotor movement between the engine and rotor, a connector between said rotor and piston, and a connector stuffing box carried by and positioned within the said head.

5. In a pneumatic engine starter, the combination of a rotor casing, a hollow head projecting therefrom, a tangentially disposed cylinder screw threaded into said head, a piston within the cylinder, a rotor, a connection between the rotor and engine, a flexible connector, one end portion of which is wound upon the rotor, the other end being connected to the piston, an annular flange within said head, and a connector stuffing box secured to said flange.

In testimony whereof I hereunto set my hand in the presence of two subscribing witnesses.

JOHN DESMOND.
